(57) **CLAIM**

The ornamental design for an image display device with tuner and digital video disc player for automobile, as shown and described.

DESCRIPTION

FIG. 1 is a perspective view of front, top and right side of an image display device with tuner and digital video disc player for automobile showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

A rear view is omitted because it is unornamental and forms no part of the subject matter of the claimed design.

The portions of the article in broken lines form no part of the claimed design.
